UNITED STATES PATENT OFFICE.

MARC H. DAUDY, OF PHILADELPHIA, PENNSYLVANIA, ASSIGNOR TO NORTH AMERICAN LACE COMPANY, OF PHILADELPHIA, PENNSYLVANIA, A CORPORATION OF PENNSYLVANIA.

DESIGN FOR LACE.

57,513.

Specification for Design.

Patented Apr. 12, 1921.

Application filed January 22, 1920. Serial No. 353,337. Term of patent 3½ years.

To all whom it may concern:

Be it known that I, MARC H. DAUDY, a citizen of France, residing in Philadelphia, Pennsylvania, have invented a certain new, original, and ornamental Design for Lace, of which the following is a specification, reference being had to the accompanying drawing, forming part thereof, in which the figure is a plan view of a piece of lace illustrating my new design.

I claim:

The ornamental design for lace, substantially as shown.

MARC H. DAUDY.
